HORATIO B. BECKMAN, OF NEWBURG, NEW YORK.

Letters Patent No. 81,976, dated September 8, 1868.

IMPROVEMENT IN STEAM SAFETY-VALVES.

The Schedule referred to in these Letters Patent and making part of the same.

TO ALL WHOM IT MAY CONCERN:

Be it known that I, HORATIO B. BECKMAN, of Newburg, in the county of Orange, and State of New York, have invented a new Improvement on Safety-Valves for Steam-Boilers; and I do hereby declare that the following is a full, clear, and exact description thereof, reference being had to the annexed drawings, and to the letters of reference marked thereon.

The nature of my invention consists in providing the safety-valve with one or more elliptical springs, standing upright on top of the safety-valve, with their lower ends in grooves on the upward side of the valve, the upper ends being kept in their places by a disk, which has corresponding grooves cut out on its lower face for their reception. By means of stud-bolts and nuts, this upper disk can be screwed down or up, to regulate the spring-power of those springs, they being the stiffer, the straighter they are, and the combined resistance of these springs on the safety-valve against pressure from the bottom side of the safety-valve can be so regulated as to balance the pressure from below, and allow the safety-valve to open as soon as the highest pressure is arrived at allowed to be carried in the steam-boiler to which the valve is attached. The elasticity of the springs also allows the valve to open high enough to give the required opening, corresponding to the area of the safety-valve.

The use of elliptical springs has the advantage over spiral springs for this reason, that they do not press with more power on the safety-valve when it is open than at the moment it is going to open. Spiral springs, being compressed, work harder, and the pressure below the valve must increase to open the valve high enough to the full area of the safety-valve. The elliptical springs work with nearly equal pressure during the time the valve is open and when it is shut.

At different trials, these elliptical springs let the valve open always at the same amount of pressure, they having been bent more or less; and when they were bent until they broke, shortly before they broke they let the valve open at the same height of pressure as when they were only bent the least, to give them the outward direction to bend.

To protect the springs from being broken by opening the valve too high, the stem of the valve is guided on its upper end in a corresponding opening in the top of the cover, which allows free opening to the valve to the required height, but which arrests the further opening, and relieves the springs from over-pressure. The valve can be lifted by hand, by means of a lever fastened in the outside shell of the valve-chamber, but the valve cannot be pressed down by any outside power.

This safety-valve is so arranged as to make it a lock-up valve. The outside shell covers the whole valve and chamber, and is fastened by a latch to the lower part of the safety-valve chamber, and securely locked. No access can be had to the valve by the way of the escape-pipe, as this pipe is cast on the outside shell, and separated from the valve-chamber by a solid wall, which is perforated only on the opposite side of the escape-pipe nozzle, to let the steam escape through the narrow space between the valve-chamber and the outside cover.

Figure 1 shows a vertical longitudinal section through the centre of the valve-chamber and the valve.

Figure 2 represents a transverse section of the upper part of the outside case.

Figure 3 is a cross-section of the lower part of the valve-chamber and outside case.

A is the safety-valve.

B, the valve-stem, which has attached to it a slotted piece, H, for the reception of the one arm of the lever L L², to lift the valve from outside.

D is the valve-chamber, which is perforated by some holes above the valve, for the escape of the steam through its side in the annular space around the chamber D', and through the escape-pipe R. On the upper part of the valve-chamber, in suitable bosses in its circumference, are fastened studs P¹ P², which keep in its place a plate, C, which, with corresponding grooves, rests on the upper ends of the springs s¹ s², the lower ends of which stand in grooves on top of the safety-valve. By means of the studs P¹ P² and plate C, these springs s¹ s² can be bent more or less to regulate the pressure of the springs on the valve, to balance the pressure on the valve from below to a certain point.

The outer case E E covers the whole valve-chamber, and leaves an annular space between its inner side and the outside of the valve-chamber D', for the escaping steam to pass out the escape-pipe R. A joint is made between those two chambers, near the bottom, by a screw-joint, or in any other way. An eye, K, is cast on the outer case E, which, in connection with the latch M and lug N, serves to secure the outer case E to the inner chamber D', by means of a padlock through the eye K, so that the outer case E cannot be removed without taking off the padlock, and any other access to the valve is made impossible.

The lever L¹ L L² has its fulcrum in the shell of the outer case F, and serves to lift the valve A by hand at any time from outside, but it is so arranged that the point, L², cannot press on the valve-stem to keep the valve down.

In the top part, G, of the case F, is a cylindrical hole, for the guidance of the stem H, and is of a depth sufficient to let the valve lift enough to give sufficient area for the steam to escape, but it arrests the valve at that point, and prevents the breaking of the springs by too much bending.

What I claim as my invention, and like to secure by Letters Patent, is—

The arrangement of the safety-valve A, adjustable elliptical springs s¹ s² s³, and plate C, substantially as herein specified.
